NAIL POLISH APPLICATOR

Vernon D. Griffith, 1639 Lexington, Wichita, Kans.

Filed Aug. 27, 1962, Ser. No. 71,453

Term of patent 14 years

(Cl. D86—10)

Fig. 3.

Fig. 2.

Fig. 4.

FIG. 1 is a perspective view of a nail polish applicator, showing my new design.

FIG. 2 is a section line 2—2 of FIG. 1 thereof;

FIG. 3 is an elevational view of one end thereof; and

FIG. 4 is an elevational view of the opposite end of my nail polish applicator.

I claim:

The ornamental design for a nail polish applicator, as shown.
